UNITED STATES PATENT OFFICE

WILLIAM E. ULRICH, OF DETROIT, MICHIGAN.

JOINT FOR INTERSECTING METALLIC MEMBERS.

1,012,761.

Specification of Letters Patent. Patented Dec. 26, 1911.

Application filed March 15, 1911. Serial No. 614,540.

To all whom it may concern:

Be it known that I, WILLIAM E. ULRICH, citizen of the United States, residing at Detroit, county of Wayne, State of Michigan, have invented a certain new and useful Improvement in Joints for Intersecting Metallic Members, and declare the following to be a full, clear, and exact description of the same, such as will enable others skilled in the art to which it pertains to make and use the same, reference being had to the accompanying drawings, which form a part of this specification.

My invention relates to an improvement in metallic framing, more especially window sash or like structures, shown in the accompanying drawings and more particularly set forth in the following specification and claims.

The object of my invention is to provide a locking joint for intersecting mullions, and the sash-frame, in which the regular commercial shapes of iron are employed to form the cross bars and frame of the structure,— the resulting sash being exceedingly strong and symmetrical in appearance.

A further object is to provide a joint simple and inexpensive in construction and one in which both intersecting members are provided with continuous unbroken portions alternately overlapping the point of intersection, thereby providing a structure interlocked in such a manner as to insure against separation at the joint and adapted to resist all strains it may be called upon to bear.

In the drawings accompanying this specification: Figure 1 is a fragmentary perspective view of a pair of intersecting cross mullions as they appear assembled and in locked relation. Fig. 2 is a fragmentary perspective view with parts broken away, indicating the manner of engaging the web of an intersecting member with the web of the cross member. Fig. 3 is a fragmentary perspective view with parts broken away of one of the mullions engaged with the frame of the sash. Fig. 4 is a fragmentary perspective view of an intersecting mullion engaged with the frame of the sash. Fig. 5 is a fragmentary perspective view of the sash frame with the web portion punched to receive the projecting end of the cross mullions. Fig. 6 is a detail perspective view of the end of the web and head or flange of a cross mul-

lion. Fig. 7 is a fragmentary perspective view of the web of a cross mullion punched and spread apart to receive the web of the intersecting mullion, as indicated in Fig. 2. Fig. 8 is a fragmentary perspective view of the cross and intersecting mullions engaged with the frame of the sash, parts being broken away to condense the view. Fig. 9 is an elevation of the sash.

Referring now to the letters of reference placed upon the drawings:—A is the frame of the sash; B the vertical sash bars or mullions.

C indicate the horizontal mullions formed of a web portion C' and a head or flange portion C², separate from the web portion. The web portion C' is punched as indicated at c in Fig. 7, to receive the web of the intersecting mullion B,—the web being divided at c' in order that the wall surrounding the aperture may spread apart for the reception of the mullion B, in turn notched at b, b, to receive the wall c², c², of the web C'. The flange of the mullion B is also cut away as indicated at B',—the web being punched as shown at B² for the passage of the head or flange C² of the mullion C.

As shown in Fig. 5, the frame A is punched at A' to receive the projecting ends of the mullion C,—the ends of the web and head portion of the mullion C being formed with projecting tongues C³ and C⁴, respectively, which after insertion in the frame are riveted thereto. The ends of the vertical mullions are also provided with a projecting tongue B³ set in apertures provided in the frame and riveted thereto, as indicated in Fig. 8.

Having denoted the several parts by reference letters, the construction and manner of assembling the same will be readily understood.

In order to place the web C' in condition to receive the web of the intersecting member B, the divided bridge wall at the end of the aperture c is first spread apart as previously stated. The web of the intersecting mullion may then be inserted as indicated in Fig. 2;—the web C' is then restored to its initial condition thus connecting the intersecting webs of the mullions B and C together. The flanges c² of the mullions C are next inserted through the apertures B² provided in the mullions B, and spot welded if

desired to the webs,—the ends of the mullions B and C being riveted to the frame A as indicated in Fig. 8.

Having thus described my invention, what I claim is:—

- 5 1. The combination of two intersecting mullions one of said mullions having its web notched and portions of its flange removed for the passage of the intersecting 10 mullion, the intersecting mullion constructed with an independent web and flange portion assembled to form a T-shaped bar, the web portion being slotted to receive the web of the first named mullion, the wall bridging 15 the slotted portion being divided at one end of the slot whereby said web may be bent to receive in the slot the web of the first named mullion, the bent portion of the web being subsequently restored to its initial 20 condition whereby the webs of said cross members are interlocked, and the independent flange portion of the T-shaped bar, intersecting the first named mullion through the opening therein provided for its passage.
- 25 2. The combination of two intersecting members one of which is cross-shaped in section, said cross-shaped bar having portions of its flanges and web removed for the 30 passage of an intersecting member, the intersecting member composed of two separate bars assembled in T-shaped form, the flange portion of the T-shaped member extending continuously and unbroken through 35 the web and flange of the first named mem-

ber, the web portion of the T-shaped member being slotted and the wall at the end of the slot divided whereby the web may be bent to receive in the slot the web of the intersecting bar, said bent web portion being 40 subsequently restored to its original condition to close around the web of the intersecting member whereby they are interlocked.

3. The combination of two intersecting mullions, one of said mullions cross-shaped 45 in section having portions of its flanges removed and its web notched and slotted for the passage of the intersecting mullion, the intersecting mullion constructed of separate web and flange portions assembled in T- 50 shaped form, the web of the latter being slotted to receive the web of the cross-shaped mullion, the wall at one end of the slotted portion divided whereby the web may be bent to receive in the slot the web of the 55 cross-shaped mullion, said bent web being afterward restored to its original condition to embrace the web of the cross-mullion, and the independent flange portion set in the slot of the cross-mullion above the separate web portion to which it is subsequently welded, whereby continuous undivided portions of each intersecting member alternate and overlap the other.

In testimony whereof, I sign this specification in the presence of two witnesses.

WILLIAM E. ULRICH.
